UNITED STATES PATENT OFFICE.

JAMES A. BECHER, OF CHICAGO, ILLINOIS.

DIE-HEAD.

1,102,712.

Specification of Letters Patent.

Patented July 7, 1914.

Application filed July 3, 1913. Serial No. 777,362.

To all whom it may concern:

Be it known that I, JAMES A. BECHER, of Chicago, in the county of Cook and State of Illinois, have invented certain new and useful Improvements in Die-Heads; and I do hereby declare the following to be a full, clear, and exact description of the invention, such as will enable others skilled in the art to which it appertains to make and use the same.

This invention relates to improvements in die heads and more particularly to simple and efficient means for mounting, manipulating and adjusting the parts which carry the dies or cutters, and the invention consists in certain novel features of construction and combinations of parts as hereinafter set forth and pointed out in the claims.

In the accompanying drawings; Figure 1 is a side elevation of a die head and operating mechanism embodying my invention; Fig. 2 is a face view of the same; Fig. 3 is a sectional view on the line 3—3 of Fig. 1; Fig. 4 is a view in section on line 4—4 of Fig. 1, and Fig. 5 is a sectional view on the line 5—5 of Fig. 2.

1 represents a barrel or tubular shaft section, to be connected in any suitable manner with a driving element. The barrel 1 is externally threaded at one end for the reception of a flanged collar 2 which forms a bearing for a cushion abutment 3 for a purpose hereinafter explained. At its forward end, the barrel is made with a head 4 which carries two jaws 5—5. Each of said jaws is made with a semi-circular enlargement 6 having recesses for the accommodation of dies or cutters 7 which are held in place by the heads of screws 8 (one side of each of which screw-heads is flattened to facilitate the insertion and removal of the dies) and the end thrust of said dies is sustained by suitable posts 8^a fixed to the jaws. The jaws 5—5 coöperate to form an elongated divided die head, and are separated from each other on diagonal parallel lines, as indicated in Fig. 2. Above and below or at respective sides of the central opening of the divided die head, springs 9—9 are disposed between the two jaws.

forming said die head. Each jaw 5 is pivotally attached near one end, to the head 4. In effecting such pivotal connection, a sleeve 10 (Fig. 5) passes through and is made fast in a hole in the head 4 and passes loosely through a hole in the adjacent jaw. A bolt 11 passes through the sleeve 10 and is threaded at one end for the reception of a nut 12. The bolts 11 also pass through plates 13 and are provided with heads 14 to engage said plates and hold them in place. The plate 13 thus attached to one jaw, overlaps the other jaw and said plates thus serve to hold the jaws properly in place against the head 4. By connecting the jaws 5 with the head 4 in the manner above explained, adjustment for wear of the jaws against the face of the head 4 can be readily made. Such adjustment may be effected by removing jaws and filing the outer ends of the sleeves 10.

An annular disk 14 encircles the barrel 1 and is movable lengthwise of the latter between the head 4 and the abutment 3, being caused to move toward the latter by means of springs 15 interposed between said disk and the head 4 of barrel 1, and being movable in the opposite or forward direction by means which will be presently explained. The disk 14 is provided at diametrically opposite points with recessed arms 16 and with sockets or perforations, in which forwardly projecting pins 17 are secured. The pins 17 project forwardly through recesses 18 in the head 4 and their conical or tapering ends 19 are adapted to coöperate with beveled shoes 20 secured (at diametrically opposite points) to the respective jaws 5. It is apparent that if the disk 14 be moved forwardly, the coöperation of the tapering forward ends of the pins 17 with the shoes 20, will cause the jaws 5 to approach each other and the dies to engage the work.

The disk 14 is made with an annular flange or hub 21, on which a ring 22 is loosely mounted so as to be immediately in rear of the butt ends of the pins 17. A yoke 23 encircles the ring 22 and is pivotally connected at diametrically opposite

points with said ring 22, by means of pivot pins 24 carried by said yoke in horizontal alinement with each other. The yoke 23 is made with an upwardly projecting arm 25 provided at its upper end with rearwardly projecting wings 26 which freely embrace the forward portion of a guide arm 27 adapted to be secured to the head-stock (not shown) of the machine on which my improvements may be used. The yoke 24 is also provided with a depending arm 28 which terminates near a bracket 29 adapted to be secured to the bed (not shown) of the machine. A shaft 30 is mounted in the bracket 29 and is provided with a forwardly projecting arm 31 and a rearwardly projecting arm 32. The bracket 29 is provided with a rearwardly projecting arm 33 disposed over the arm 32 and a set screw 33^a passes downwardly the said arm 33 in position to be engaged by the arm 32 and thus limit the movement of the shaft 30. An operating lever 34 is also secured to the shaft 30 and movement of the latter in the opposite direction to that above referred to, will be limited by engagement of said operating lever with a spring arm 35, as shown by dotted lines in Fig. 1. A set screw 36 passes horizontally through the upper arm 25 of the yoke 23 and engages the free end of the fixed arm 27, for the purpose of adjustments which will be hereinafter explained.

In the drawings, the parts are shown, in full lines, in the positions which they will assume when in operation, the dies being set, and the parts which carry and control them, being locked by reason of the fact that the arm 31 on shaft 30 is disposed exactly at right angles to the lower arm 28 of the yoke, which is pressing against said arm. In other words, the arm 31 and the shaft to which it is secured are on a dead center with respect to the pressure of the yoke 23 against the free end of said arm. Let it be assumed that when the parts are in their working positions as shown in full lines in the drawings and that it is desired that the dies shall be made to cut a little deeper. This may be accomplished by adjusting the set screw 36 so as to move the yoke slightly in a forward direction. The result of such slight forward adjustment of the yoke, will be a slight forward movement of the disk 14 and the pins 17, and coöperation of said pins with the beveled shoes 20 on the jaws 5, will cause sufficient inward movement of the latter to effect the desired adjustment of the dies for a deeper cut. By adjusting the screw 36 in the reverse direction, the pins 17 will be permitted to move rearwardly (by the operation of the springs 15) and the jaws 5 will be caused to recede by the action of the springs 9, thus reducing the

depth of cut of the dies. The adjustments 65 may be effected without stopping the machine. When it is desired to open the jaws composing the divided die head, the operator will move the hand lever 34 rearwardly to raise the arm 31. The springs 15 will 70 now be free to move the yoke 23, disk 14, pins 17 and ring 22, rearwardly, thus withdrawing the pins from the jaws 5 and permitting the latter to be opened by the action of the springs 9. The lever 34 will be 75 limited in its rearward movement by engagement with the spring arm 35, and disk 14 and parts carried thereby will be cushioned by the abutment 3.

It is apparent that when the operating 80 lever 34 is moved forwardly from the dotted line position to the full line position shown in Fig. 1, the yoke 23 and disk 14 will also be moved forwardly (compressing the springs 15) and that the coöperation of 85 the tapering ends of the pins 17 with the jaw shoes 20 will cause the jaws to be closed and the dies moved to operative positions.

Having fully described my invention what 90 I claim as new and desire to secure by Letters-Patent, is:—

1. The combination with a support, of die-carrying jaws pivotally attached to said support, a guide plate attached to each jaw and projecting over the other, and means 95 for operating said jaws.

2. The combination with a barrel provided at one end with a head, of sleeves secured to said head, and projecting beyond 100 the same, die-carrying jaws loosely mounted on said sleeves, and bolts passing through said sleeves, each of said bolts provided at its ends with heads, one of which is removable.

3. The combination with a barrel having a head at one end and sleeves secured to and projecting beyond said head, of die-carrying jaws pivotally mounted on said sleeves and bearing against said head, bolts passing 110 through said sleeves, and guide plates for the jaws held in place by said bolts.

4. The combination with a die head, dies carried thereby, operating means for said dies, and a fixed arm, of a yoke embracing 115 said operating means and pivotally connected therewith, said yoke having an arm provided with wings, loosely embracing said fixed arm, a set screw passing through said yoke arm and engaging the fixed arm, said yoke having another arm, and a lever co-operating with said last-mentioned arm to move the yoke.

5. The combination with a die head, dies carried thereby, operating means for said 125 dies, and a fixed arm, of a yoke embracing said operating means and pivotally connected therewith, said yoke having an arm pro-

jecting in one direction therefrom and co-operating with the fixed arm, said yoke having another arm, a shaft, an arm projecting from said shaft and adapted to engage 5 the last-mentioned yoke arm, a lever secured to said shaft, and a stop for said lever.

In testimony whereof, I have signed this

specification in the presence of two subscribing witnesses.

JAMES A. BECHER.
